(57) **CLAIM**

The ornamental design for an electric insect eliminating racket device, as shown and described.

DESCRIPTION

FIG. 1 is a front view of an electric insect eliminating racket device showing my new design;

FIG. 2 is a side view thereof;

FIG. 3 is an opposite side view thereof;

FIG. 4 is a rear view thereof;

FIG. 5 is a perspective view thereof;

FIG. 6 is a top view thereof; and,

FIG. 7 as a bottom view thereof.

The broken lines illustrate environmental structure and form no part of the claimed design.
